UNITED STATES PATENT OFFICE

OTTO WUNDRACK, OF PITTSBURGH, PENNSYLVANIA

BAKER'S OVEN

Application filed July 15, 1930. Serial No. 468,186.

My invention relates to improvements in baker's ovens of the character known as "tray ovens" and employing an endless conveyor; the present invention being particularly directed to the generation of heat and the circulation of the heating medium for such ovens, whereby maximum efficiency is provided with a minimum consumption of fuel.

10 My invention contemplates providing an oven of the character designated with a plurality of independently regulable furnaces or fire-boxes to comprise a multiple furnace system, the number and arrangement of the 15 furnaces or fire-boxes being dependent upon the length and size of the oven to which they are applied. The said furnaces or fire-boxes lend themselves to automatically operable means for controlling the fuel supply 20 to better advantage than in the old style of heating.

An important object is to provide equalizing chambers associated with the furnaces or fire-boxes and disposed entirely within the 25 oven, said equalizing chambers being operable to deflect the heating medium from the furnaces by means of baffles in such a manner as to uniformly distribute said medium throughout the oven.

30 A plurality of flues are provided in open communication with the equalizing chambers for conducting the heating medium longitudinally and transversely of the oven, to be exhausted therefrom by means of a suction 35 fan or other draft means, said medium being subjected to pressure and utilized for combustion in the furnaces.

An additional feature is to so arrange and 40 construct the furnaces or fire-boxes, equalizing chambers and flues as to constitute a series of baffles for confining the heat produced by the passage of the heating medium therethrough to the various runs or flights of the circuitous conveyor.

45 My invention may be more readily understood by reference to the following specification taken in connection with the accompanying drawings, wherein:

50 Fig. 1 is a longitudinal sectional view of a baker's oven embodying my invention;

Fig. 2, a transverse section taken on the line II—II of Fig. 1;

Fig. 3, an enlarged detail sectional view of the furnace construction, said section being taken on the line III—III of Fig. 1;

Fig. 4, a cross-section on the line IV—IV of Fig. 3 showing the furnace or fire-box and the equalizing chamber;

Fig. 5, a view similar to Fig. 4, showing a modified form of furnace or fire-box construction; and

Fig. 6, a diagrammatic view in side elevation of the oven, particularly showing means for utilizing the heating medium for combustion.

Referring to the drawings, the baker's oven A is generally rectangular in form, the walls thereof being constructed of suitable heat insulating material and entirely enclosed with in an outer casing a. Mounted therein and adapted to travel in a circuitous path, I provide a conveyor system including a plurality of sprockets 2, continuous link chains 3 having suitable rollers 4 thereon for supporting the conveyor upon trackways 5, and a plurality of transversely extending trays 6. Said trays are pivotally mounted upon the link chains by means of trunnions 7, and extend substantially the width of the interior of the oven. The conveyor proper may be driven by any suitable means; as illustrated, 2a designates the drive sprocket fixedly mounted on a drive shaft 8 and connected with a suitable power source not shown.

As is customary in baker's ovens of the character shown, the sprockets 2 are so positioned as to provide a series of substantially horizontal runs or flights for the conveyor in a circuitous path. Such construction permits of the application of heating means to said series of runs or flights to produce the desired baking temperatures.

To this end I provide a plurality of oven furnaces or fire-boxes 8, 8a and 8b, extending transversely of the oven A and positioned one above the other in staggered relation directly beneath different runs or flights of the conveyor, as shown in Fig. 1. Said furnaces or fire-boxes are disposed entirely within the oven structure and are constructed of fire

brick or other refractory material. One end of each of said fire-boxes is open as at 9 for the purpose of introducing the heating means into the fire-boxes.

5 In the form of Figs. 3 and 4, I have shown said opening adapted to the insertion of an oil or gas burner 10, but the same may be larger for the introduction of other means, as for example coal, which is used in connection 10 with the grate construction shown in Fig. 5. Ready access is had to the furnaces or fire-boxes at their open ends by means of the open recesses 11 in the walls and casing of the oven.

15 When oil burners are employed, a baffle 6 is provided midway of the furnace or fire-box upon which the burner flame impinges, thereby giving more efficient combustion.

20 The side walls 12 and the bottom walls 13 of the furnaces or fire-boxes are preferably constructed of heat resisting refractory material, as for example, fire brick. The top walls 14 are formed of efficient heat conducting and radiating material such as fire tile. Said walls are encased in metallic coverings 15, including top plate members 16 extending throughout the length of the furnaces. Thus it will be seen that the top walls 14 and the plates 16 constitute radiating surfaces for 30 utilizing the direct heat produced in the furnaces or fire-boxes.

25 A side wall 12 of each of the furnaces is formed with a plurality of spaced-apart openings 17 immediately below the top walls 14 of said furnaces, and in communication with equalizing chambers 18 extending longitudinally of the furnaces. Said equalizing chambers are disposed entirely within the oven and have bottom and side walls 19 and 20 respectively, formed of refractory material. The tops of the chambers comprise heat 35 conducting metal plate members 21 having longitudinally extending flanges 22 along one edge thereof for joining with the plates 16 of the furnaces or fire-boxes. Metal casing 22a is provided around the said bottom and side walls.

40 Depending from said plate members 21 and extending longitudinally thereof, I provide baffles 23, preferably formed integral with the plate members and designed to divide the interiors of the chambers 18 for the purpose of deflecting the heating medium passing from the furnaces or fire-boxes. Delivery openings 24 are provided in the upper portions of the walls 20, the same being on the opposite side of the baffles 23 from the openings 17 to the interior of the fire-boxes. The 45 openings 24 are furnished with flue connection members 25 secured in place by joining to the plate members 21 in any suitable manner.

45 The heating medium or hot gases passing from the furnaces by means of the openings 17 are deflected downwardly and thence upwardly around the baffles 23, as indicated in

the drawings, thereby effecting a uniform distribution of said medium for delivery through the flue connections 25.

50 As illustrated in Fig. 1 the furnaces or fire-boxes 8, 8a and 8b are positioned one above the other in staggered or stepped relation within the oven, each of said furnaces being directly beneath a run or flight of the conveyor, and spaced therefrom a sufficient distance to permit the travel of the trays 6 thereover. The furnace 8 and its equalizing chamber 18 are located beneath the first run or flight of the conveyor.

55 For the purpose of heating the space through which said conveyor flight passes, I provide a plurality of longitudinal heating flues 26 extending forwardly of the oven and in open communication with the flue connections 25 of an equalizing chamber 18 associated with the furnace 8. Said heating flues are preferably formed with a bottom wall 27 constructed of sheet metal, side members consisting of out-turned channels 28, and heat conducting and heat radiating top members 29. The portions of the flues just described may be secured together in any suitable manner, as by welding. The top members 29 are preferably corrugated as shown for increasing the effective heat radiating surfaces thereof.

60 Similarly, the furnace or fire-box 8a is provided with heating flues 26a extending longitudinally of the oven and immediately below the second flight of the conveyor. The flues 26a are constructed in the same manner as the flues 26, and the parts thereof have been so designated.

65 Also, the furnace or fire-box 8b is provided with similar flues 26b for heating the space through which the last or lowermost flight of the conveyor passes, said flues also comprise the same parts as the flues 26 and 26a, and are similarly joined to their respective fire-boxes by means of the connections 25.

70 The aforesaid heating flues are adapted to communicate with transverse heating medium conveyor flues entering into the construction of the multiple furnace system. That is, the heating flues 26 are in open communication with the transverse heating medium conveyor flue 30, heating flues 26a with transverse flue 30a, and heating flues 26b with the transverse flue 30b. In addition, another transverse flue 30d is provided immediately below the uppermost flight of the conveyor system in vertical alinement with the transverse flue 30b, said flues being in open communication at their ends with vertical connecting flues 31 formed in the side walls of the oven.

75 Similarly, the transverse flues 30 and 30a are in vertical alinement for communication at their ends with vertical flues 32 also formed in the side walls of the oven. 33 designates flues for conducting the heating me-

dium from the vertical flues 32 into the flues 31 to provide a continuous path for said medium.

The heating medium from the several furnaces or fire-boxes passes through the respective heating flues, transverse conveyor flues and upwardly by means of the vertical flues 31 and 32 into transverse flue 30d, where it is passed rearwardly of the oven and beneath the uppermost flight of the conveyor through heating flues 26d. Said flues 26d terminate in a transverse flue 30e, from which the heating medium is conveyed upwardly by means of vertical flues 34 into a transverse exhaust flue 35. A motor-driven fan or exhauster 36 is provided to draw the heating medium from the flue 35 and the entire system to pass into the atmosphere, or utilized in the manner hereinafter set forth.

It is to be noted that the longitudinal heating flues 26, 26a, 26b and 26d together with their respective fire-boxes constitute baffles for confining the heat generated by the passage of the heating medium therethrough to the several runs or flights of the conveyor system, thereby facilitating the control of the baking temperatures at each of said flights. In addition, a series of horizontally extending baffles 37 are provided between said flights.

Also, an irregular baffle 38 is positioned rearwardly of the horizontal conveyor flights to maintain the temperature within the baking area and prevent excessive heating during the return or vertical flight 39 at the rear of the oven.

In operation, the bread or other substance to be baked is applied to the trays 6 through the oven doors 40. During the first part of its travel, the bread is subjected to steam by means of steam pipes 41 to supply moisture and give color thereto. The conveyor then carries the bread through its successive flights where the bread is subjected to the various baking temperatures, controlled by means of the fire-boxes and the flue system hereinbefore described. When the bread again reaches the doors 40 it is completely baked and may be removed and the trays reloaded.

Suitable dampers 42, 42a, 42b and 42d are provided at the forward ends of the heating flues 26, 26a, 26b and 26d respectively and are so arranged on transverse damper rods 43 as to effectively control the passage of the heating medium. In the drawings, the heating flues are shown in groups of three and the dampers are so designed that any number thereof may be opened for the passage of the heating medium. The damper rods 43 extend outside the oven proper for manual operation.

For the purpose of utilizing the heating medium or hot gases in connection with the oil or gas burners 10, the same is withdrawn from the flue system by means of the fan or exhauster 36 and passed into an exhaust con-

duit 44, which is in open communication with a vertical conduit 45 having a booster fan 36a therein for increasing the pressure of said gases before passing to the burners. The gases pass from the fan into a manifold 46 from which they are conveyed to the burners 10 by individual pipes 47. Fuel, as oil or gas, is supplied to said burners by means of pipes 48 and the supply line 49. When desired, the gases may be exhausted or partially exhausted to the atmosphere, as at 50, by opening damper 51 and closing the damper 52 in the conduit 45.

During the operation of the oven, the air in the space *c* between the walls thereof and the outer casing *a* becomes heated. Said heated air may also be utilized in the burners 10 by means of a connecting conduit 53 between the casing and the conduit 45, and having a damper 54 therein for regulation and control.

Referring to Fig. 5 and as stated, the fire-boxes or furnaces may be so constructed as to accommodate coal as a fuel. Thus the fire-box 8c is provided with a grate 55 for burning pea coal, said grate having openings 56 therethrough for the introduction of air from a lower chamber 57 supplied by a conduit 58 which may enter into the system for utilization of the gases or heating medium described supra.

Secondary air from the same or other suitable source may be introduced into the equalizing chamber 18, as at 59, by means of a conduit 60. The remaining parts of the fire-box and equalizing chamber are the same as in the form employed with an oil or gas burner, and have been so designated.

I claim:

1. In a baker's oven, a baking chamber, a conveyor operable within the chamber, a plurality of fire-boxes each disposed entirely within the oven equalizing chambers extending parallel with said fire-boxes, and heat medium conveyor flues communicating with the equalizing chambers and extending longitudinally and transversely of the baking chamber, said fire-boxes having openings on the sides thereof adjacent the equalizing chambers.

2. In a baker's oven, a baking chamber, a conveyor operable within the chamber, a plurality of fire-boxes each disposed entirely within the oven equalizing chambers extending parallel with said fire-boxes, and heat medium conveyor flues communicating with the equalizing chambers and extending longitudinally and transversely of the baking chamber, said fire-boxes arranged in different horizontal planes, said fire-boxes having openings on the sides thereof adjacent the equalizing chambers.

3. In a baker's oven, a baking chamber, a conveyor operable within the chamber, a plurality of fire-boxes each disposed entirely within the oven equalizing chambers extend-

- ing parallel with said fire-boxes, and heat medium conveyor flues communicating with the equalizing chambers and extending longitudinally and transversely of the baking 5 chamber, said fire-boxes arranged in different horizontal planes and in staggered relation, said fire-boxes having openings on the sides thereof adjacent the equalizing chambers.
- 10 4. In a baker's oven, a baking chamber, a conveyor operable within the chamber, means for effecting a plurality of horizontal flights of the conveyor, and a plurality of independent fire-boxes disposed within the 15 oven and extending thereacross, one of said fire-boxes located between two horizontal flights of the conveyor equalizing chambers extending parallel with said fire-boxes adjacent thereto and in communication there- 20 with throughout its length, and heat medium conveyor flues communicating with the equalizing chambers and extending longitudinally and transversely of the baking chamber.
- 25 5. In a baker's oven, a baking chamber, a conveyor operable within the chamber, a fire- 30 box disposed entirely within the oven and extending transversely thereacross, a heat medium distributing and equalizing chamber arranged parallel with the fire-box and 35 in communication therewith at the side thereof, a baffle in said chamber extending longitudinally thereof across the communicating opening between said chamber and the fire- 40 box and terminating short of the bottom of 45 the said chamber, and a heat medium conveyor flue in communication with said chamber, said last mentioned flue extending longitudinally of the baking chamber.
- 50 6. A baker's oven, comprising in combina- 55 tion, a baking chamber, a conveyor operable within the baking chamber, means for effecting a plurality of horizontal flights of the conveyor, a plurality of independent fire- 60 boxes disposed transversely within the oven 65 at different levels and having a plurality of openings at the sides thereof, an equalizing chamber parallel with and adjacent to each of said fire-boxes on the side where said open- 70 75 80 85 90 95 100 105 110 115 120 125 130 ings are located, baffles extending through- out the length of said equalizing chambers 120 and terminating short of the bottom thereof, and heat conveyor flues connected to each of said equalizing chambers and extending partially longitudinally of the oven.
- 75 7. A baker's oven, comprising in combina- 80 tion, a baking chamber, a conveyor operable within the baking chamber, means for effecting a plurality of horizontal flights of the conveyor, a plurality of independent fire- 85 boxes disposed transversely within the oven 90 at different levels and having a plurality of openings at the sides thereof, an equalizing chamber parallel with and adjacent to each of said fire-boxes on the side where said open- 95 100 105 110 115 120 125 130 ings are located, baffles extending throughout

the length of said equalizing chambers, and heat conveyor flues connected to each of said equalizing chambers and extending partially longitudinally of the oven to a common outlet.

In testimony whereof I affix my signature.
OTTO WUNDRACK.
